UNITED STATES PATENT OFFICE

147,828

DESIGN FOR A HIGH CHAIR

Edwin L. Beckwith, West Newton, Mass.

Application April 6, 1946, Serial No. 128,358

Term of patent 14 years

(Cl. D15—1)

To all whom it may concern:

Be it known that I, Edwin L. Beckwith, a citizen of the United States, residing at West Newton, in the county of Middlesex and Commonwealth of Massachusetts, have invented a new, original, and ornamental Design for a High Chair, of which the following is a specification, reference being had to the accompanying drawing, forming a part thereof, in which:

Fig. 1 is a fragmentary view in perspective of a high chair showing my new design, and

Fig. 2 is a corresponding view of the high chair as seen from the rear.

I claim:

The ornamental design for a high chair, substantially as shown.

EDWIN L. BECKWITH.
